WALTER STAFFORD AND ROBERT C. HOLT, OF LITTLE FALLS, NEW YORK.

KNITTING-MACHINE.

1,197,963.

Specification of Letters Patent. Patented Sept. 12, 1916.

Application filed April 27, 1916. Serial No. 94,034.

To all whom it may concern:

Be it known that we, WALTER STAFFORD and ROBERT C. HOLT, of Little Falls, in the county of Herkimer and State of New York, have invented certain new and useful Improvements in Knitting-Machines; and we do hereby declare that the following is a full, clear, and exact description thereof, which will enable others skilled in the art to which it appertains to make and use the same, reference being had to the accompanying drawings, and to the reference-numerals marked thereon, which form part of this specification.

Our present invention relates to improvements in knitting machines, and particularly to circular knitting machines which are provided with vertically operating knitting needles.

It is the purpose of our invention to provide an improved knitting machine of the class described, and particularly to provide one equipped with additional coöperating mechanism whereby the plain knitted fabric has added thereto a fleecing thread projecting in loops upon one side of the fabric and another fleecing thread projecting in loops from the other side of the fabric.

A further purpose is to provide a machine of the class described and adapted to make fabric as above described so that one series of fleecing threads will project in loops from one side only of the fabric and another series of fleecing threads will project in loops from the other side only of the fabric.

A further purpose is to provide a machine of the type mentioned of such construction and combination of parts that the fleecing threads laid into the fabric will appear in a novel way and in such a manner as to render the loops of the said fleecing thread more firm and durable than usual.

A still further purpose of our invention is to provide a machine of the class described and adapted to produce fabric as mentioned, wherein the machine is provided with improved means and combinations of means for performing the desired operations in improved, simple and efficient ways.

Further purposes and objects of our invention will appear from the specification and claims herein.

Figure 1 is a vertical sectional view through one side of a knitting machine embodying our invention. Fig. 2 is a horizontal sectional view on line 2—2 of Fig. 1 with the

vertical needles and horizontal inside and outside fingers shown on only two of the eight sections of the machine. Fig. 3 is a view on a greatly enlarged scale of the back side of the fabric produced by our machine. Fig. 4 is a view on a similar scale of the front side of said fabric. Fig. 5 is a front view of the guide 56 for supplying inside the circle of needles the thread for the outside fleecing loops, together with adjacent parts of the machine. Fig. 6 is a detail sectional view on line 6—6 of Fig. 5. Fig. 7 is a front view on line 7—7 of Fig. 8, of the guide 76 for supplying outside the circle of needles the thread for the inner fleecing loops, together with the parts adjacent to said guide. Fig. 8 is a detail sectional view on line 8—8 of Fig. 7.

Referring to the drawings in a more particular description, there will be seen the essential and well known parts of a common type of circular knitting machine, including suitable supports 20, an annular plate 21 carried thereby, having an upstanding flange 22 at its inner side, removable upward extensions 23 on said flange and usually for convenience constructed in sections, cams 24 arranged about the inner surface of said flange 22 and its extensions 23 and provided with the usual cam groove 25 opening inward to receive the heels 26 of vertically arranged and vertically moving latch needles 27, and a needle cylinder 28 having vertical slots 29 holding said needles 27 so that their heels 26 will ride in the cam groove 25 and give the needles the usual vertical or up and down movement at each feed as the cylinder 28 is rotated in the machine.

The cylinder 28 is supported in position and rotated by being mounted on an annular member 30 suitably and rotatably mounted beneath and projecting inwardly from the annular plate 21. Said member 30 is rotated by its circle of teeth 31 being engaged by a pinion 32 on shaft 33 suitably journaled in a support 20 and another exterior support 34 of the machine. Said shaft is provided with the usual tight driven pulley 35 and a loose pulley 36 and the usual hand wheel 37.

The above-described construction is a common form of circular knitting machine such as is used to produce the basic web of the fabric shown in Figs. 3 and 4 and which basic web is the common plain knit fabric

often called "stocking net" made by each needle knitting at each feed. The machine herein shown and described is what is commonly known as an eight-feed machine or 5 a machine where the needles 27 as they rotate with the cylinder 28 perform a full knitting operation at each one-eighth of the circle of the machine by reason of there being eight full sets of cams 24 equally distributed about the circle of the machine. It 10 will be understood, however, that our invention is not limited to use with an eight-feed machine, but may be utilized without change of principle even where odd number 15 of feeds are used, although in that case different appearing fabric would be produced.

In the basic web shown, from the thread 5 there are formed vertical rows of stitches or 20 wales 6 on one side of the fabric (commonly and hereinafter for convenience and definiteness called the front side of the fabric) and these stitches are severally connected to their adjacent stitches in the same horizontal course by the said basic web thread 5 extending 25 horizontally as connecting threads 7 which are located on the other side of the fabric (commonly and hereinafter called the back side of the fabric). The successive stitches of the basic fabric are formed in 30 loops passing to the front of the fabric through the loop of the preceding stitch and extending upwardly as shown in Figs. 3 and 4 of the drawings and there in turn receiving through its loop in a similar way the 35 loop in a stitch in the next course of stitches. Between each two adjacent stitches in the same course and their two connecting threads 7 are left meshes 8 shown in the drawings in the usual exaggerated form for 40 the purpose of clearness.

About the outer edge of plate 21 and suitably secured thereto are upstanding posts 38, to which at about the level of the top of the cylinder 28 is fastened a strong annular 45 ring 39 and the sectionally made cam holder 45. Below this cam holder is located the outside dial 40 which is caused to rotate in unison with the cylinder 28 as by being secured to a shoulder 41 projecting outwardly 50 from the cylinder between the needles 27. In the upper surface of the outside dial 40 are provided radially arranged slots 42 wherein are mounted the outside fingers 43. These fingers have hooks 44 at their 55 inner end or at their end toward the cylinder formed by that end of the finger being turned down and then outward, forming a hook opening downwardly and outwardly as plainly indicated in Fig. 1. Immediately 60 above the outside dial 40 is stationarily secured the cam holder 45, having inside and outside cam plates 46 and 47 respectively, leaving therebetween a cam groove 48, the shape of which is plainly indicated in dotted lines in Fig. 2. Upwardly 65

extending heels 49 on the fingers 43 extend into said cam groove 48 and rotation of the outside dial 40 will in an obvious manner cause the fingers 43 to be thrust inward past the circle of needles 27 and then be withdrawn outwardly according as the cam groove 46 approaches or recedes from the said circle of needles. The slots 42 are of such number and so arranged that the fingers 43 will pass inward in the space 70 between the adjacent needles 27 or between adjacent needles when the needles are raised. As is plainly suggested in Fig. 2, the path of the cam groove 48 for these hooked fingers 43 is divided into eight sections corresponding with the number of feeds upon the knitting mechanism proper of the machine. Four of these sections as from point 50 to 51 have the cam groove in a regular circle positioned as indicated to hold the 85 hooked fingers 43 back from the needles 27. Each of these inactive sections is followed by an operating section as from point 51 to point 55. During this operating course the cam groove 48 slants gradually inward as to 90 point 52, then outward as to point 53, then without change of distance from center to point 53^a, then inward again as to point 54 and then outward again as to point 55, which is followed immediately by point 50 at the 95 beginning of the next inactive section of the cams of said outside dial.

As the hooked fingers 43 pass inward along the cam path from points 51 to 52 the said hooked fingers are thrust inwardly between the adjacent upraised needles 27 until the parts come to the relative position shown in Fig. 1. It will be understood that at this time the needles 27 have about their shanks the last formed loops 6 of the basic 105 fabric and that the preceding fabric extends inward from the circle of needles and in a downward slanting direction over the slanting top of the cylinder 28 and is drawn downward under proper tension in any desired manner (not shown). As the cylinder 110 needles have thus been thrust upward and their loops drawn down on to their shanks the latches of said needles have been opened, leaving the needles ready to receive the basic thread 5 to be supplied at this feed 115 and immediately thereafter do receive said thread. Meanwhile, the inwardly thrust hooked ends of the fingers 43 have caught the fleecing thread 9 supplied by suitable feed member 56 which conducts the said 120 thread from a suitable source (not shown) to a point within the circle of cylinder needles to a point just below the inwardly thrust ends of the hooked fingers 43. Further rotation of the outside dial 40 moves the fingers 43 along the cam groove from point 52 to 53, bringing the fingers sharply outward, whereby the hooks 44 of said fingers engage 125 said fleecing thread 9 and draw it into loops 130

10 as the hooks of said fingers pass back between said upraised needles and to some distance therebeyond. The shanks of said upraised needles act as posts for the drawing 5 of said loops while their outward ends are engaged by the hooks of the fingers 43. While the hooked fingers 43 are passing along the cam groove from 53 to 53^a and therefore holding the loops drawn outwardly, the 10 cylinder needles pass downward and cast off the old loops of the basic fabric or form a new loop of the basic fabric through what has been heretofore called the needle end of these fleecing loops or through what should 15 now be called the fabric end of said fleecing loops. As the cam groove inclines inwardly from point 53^a to 54 the hooked fingers 43 are again moved inward and allow the free ends of these fleecing loops to become dis- 20 engaged from the hooks 44 of said hooked fingers. Then the hooked fingers 43 are withdrawn to outer or inactive position, due to the course of the cam groove from point 54 to 55. During these operations and the 25 consequent inward and downward draw upon the fabric being knit the needle ends of these fleecing loops have been transferred to the wales formed by the stitches just knit and the ends of said loops which extended 30 outward between the needles now being freed from the hooked fingers simply draw over the top of the cylinder and stay on the outside or front side of the fabric as plainly shown in the drawings and naturally tend 35 to incline toward the top of the fabric as indicated in Fig. 4, due to the downward course of the fabric along the inner surface of the cylinder 28.

Supported upon the upper ends of posts 40 38 is a spider frame 57 down through which hangs a shaft 58 located centrally of the cylinder 28. Upon this shaft 58 is revolv- 45 bly mounted the inner dial 59 having about its upper surface toward the edge a series of radially arranged slots 60, in which are slid- 50 ingly mounted the inner fingers 61. These fingers have their outer ends formed with a hook 62 similar to the hooks 44. The inner dial 59 is rotated at the same rate as the 55 needle cylinder 28 and receives its power therefrom as by the usual inter-engaging arms or inter-engaging rollers on arms project- 60 ing respectively from the lower side of said dial and the inner surface of the cylinder which parts are not shown as they are common in the art, it being understood that 65 said parts allow the knitted fabric to pass downward therebetween without interfering with the transmission of power or of the take-up of the knitted fabric.

The upwardly extending heels 63 of the hooked fingers 61 ride in the cam groove 64 left between the adjacent edges of inner and outer cam plates 65 and 66 respectively. 65 These cams are secured to the lower face of

sectional cam holders 67^a suitably secured to a main cam holder 67 stationarily mounted upon the hanging shaft 58. The course of this inner dial cam groove 64 as plainly indicated in dotted lines in Fig. 2, is also di- 70 vided into eight substantially equal sections. Four of these sections as from points 68 to 69 are inactive sections, in that the cam groove is far enough in at all points so as to keep the inner hooked fingers 61 in re- 75 tracted or inoperative position. The inner fingers 61 are also of such numbers and so arranged that when projected they extend between the upraised cylinder needles 27. These inactive sections of the inner dial are 80 located approximately opposite the active or operative sections of the outer dial. For this reason when the outer dial hooked fingers are going in past the needles and forming the loops 10 as heretofore described the 85 inner fingers opposite said operative outer fingers are not only within the circle of needles, but sufficiently inside said circle of needles as to be out of the way of the in- 90 wardly thrust ends of the outer fingers.

Following each inactive section of the inner dial cams is an operative section, ex- 95 tendsing as from point 70 to point 75. These active sections are accordingly approxi- 100 mately opposite the inoperative or inactive sections of the cams of the outside dial. The relative course of these active sections of the cams for the inside dial are as fol- 105 lows: from point 70 to 71 slanting outward, resulting in projecting the inner fingers to 100 and through the upstanding needles; from point 71 to 72, drawing the fingers back; from point 72 to 73, holding said fingers back; from 73 to 74, projecting said fingers somewhat outwardly again; and then from 105 74 to 75, withdrawing said fingers inward again. Point 75 at the end of one active course is the same as the beginning point 68 in the course of the next following inactive section.

As the needle cylinder revolves anti-clock- 110 wise as viewed from above, carrying there- 115 with the needles and the fabric knit thereon, including the loops 10 formed on the outside of the fabric as hereinabove described by the outer hooked fingers operating at an active section of the cams over the outside dial 40, the vertical needles will next be brought to another feed to form another course of stitches of the basic fabric and at 120 the same time will be brought opposite an active section of the inner cam groove 64 over the inner dial 59. This course of 125 stitches formed at this feed by the vertical needles is made by the usual up and down motion communicated in turn to each of the vertical needles as they pass through this section of the cylinder cams.

As the vertical needles 27 are moved up, 130 the old loops thereon draw down upon the

needles, open the latches of said needles, pass down over the said latches, and are held upon the shanks of the needles close to the top edge of the needle cylinder 28, 5 with the fabric already made extending down over the slanting upper edge of said cylinder and down closely along the inner face thereof as already mentioned. While the needles 27 are thus raised above the level 10 of the inner hooked fingers 61, said fingers are thrust out by reason of the heels 63 of said fingers following the course of the inner cam groove from 70 to 71 until the hooks 62 on the outer ends of said inner 15 fingers are outside the circle of upraised needles. At this point there is supplied to these hooked fingers from feed plate 76 the fleecing thread 12 which is to form the loops 13 on the inner side or connecting thread 20 side of the fabric being made. This fleecing thread 12 is supplied to the feed plate 67 from a convenient source (not shown). It is supplied to said inner fingers at a point outside the circle of upraised needles and 25 grasped by the hooks of said inner needles so that as the said fingers are withdrawn from between the upraised shanks of the needles a loop 13 of said fleecing thread 12 is drawn back between each two adjacent upraised needles as the fingers pass along 30 the cam groove from 71 to 72. Said loops are held back as the fingers pass along the cam groove from point 72 to 73. As these loops 13 of the fleecing thread are thus temporarily held drawn back from the circle 35 of needles, the needles, having received their thread for this course of loops of the basic fabric, pass downward through the old basic fabric loops on the shanks of the needles and 40 through the needle ends of the fleecing loops 13 so that the old basic web loops are cast off over the upper ends of the needles and the needle ends of the fleecing loops 13 which were outside the needles are thrown off with the needle end of the old basic web loops over the upper ends of the now depressed needles. Then there is an outward movement of the inner fingers consequent 45 upon the fingers having their heels pass in the cam groove from point 73 to 74 so that these fingers move out toward the circle of needles and thereby disengage the hooks of said fingers from the loops 13 drawn inward by said fingers. As the fingers travel along the cam groove from 74 to 50 75, they are withdrawn into inactive position ready to enter the inactive section of the cam groove from point 68 to 69, heretofore mentioned. As the fleecing loops 13 drawn by these inner fingers are drawn in over the fabric and toward the back of the fabric or the connecting thread side of the fabric the free end of said loops is upon the back or connecting thread side of said fabric. The fabric end of these loops 13, how-

ever, at no time passes in front of the wales of the fabric, but behind as plainly indicated in Fig. 3, where it will be seen that the connecting portion 14 of this fleecing thread 12 which passes from one loop 13 to the next and so forms the means of holding the loops into the basic fabric is back of the wales of the basic fabric and is held into the basic fabric by passing in front of the connecting threads 7 of the basic web. It 70 will thus be seen that in a special sense these back fleecing loops 13 not only have their free ends on the back of the fabric but have substantially the whole length of their anchoring portions or fabric ends on the back 75 of the fabric, in that these loops pass in front only of the connecting threads and not of the fabric bodily. The mechanism to readily produce this result upon plain basic fabric is especially valuable because in this 80 way a knitted fabric may be produced having a fleecing thread on one side of a different character of thread or even of a different colored thread and said fleecing thread will not be visible from the front or wale 85 side of the fabric as actually produced. The further rotation of the cylinder and inner and outer dials will successively knit another course of basic web stitches and therewith another course of outer loops will 90 be formed as hereinbefore described and then at the next feed or section of the machine another course of basic fabric stitches will be formed and therewith another course 95 of inner fleecing loops as herein described and so on until the machine completes its 100 rotation when another series of similar steps will begin in the usual way of circular knitting machines.

It will be understood of course that various modifications and changes may be made in our machine without departing from the spirit of this invention, since it will be apparent that a fleecing thread does not have to be incorporated into the fabric 105 at each feed. Furthermore, it will be noted that various modifications may be made in the combination of parts in our machine, resulting in a corresponding modification of the fabric produced such, for instance, as 110 that the inner and outer fleecing threads do not have to be put in alternately one after another, but might be changed by an obvious shifting of the cam sections controlling the inner and outer dials so that 115 two courses of outer fleecing threads might be placed into the fabric and then two courses of inner fleecing threads or one course of one and two or more of the other. The preferred form of our machine is such 120 as shown in the drawings and herein described in detail, for the reason that this arrangement produces a fabric having both of its faces well and evenly covered with fleecing loops. 125 130

The feed member 56 for supplying inside the circle of needles the thread for the outside fleecing loops has its construction and arrangement shown in detail in Figs. 5 and 6 particularly. This feed member 56 consists of a vertical part 56^a and a horizontal arm 56^b. The member is arranged just outside the cam holder 67^a for the inner dial and within the circle of needles 27. The upright part 56^a comes down in front of the cam holder 67^a at a point where both the inner and outer hooked fingers are in inoperative position. The horizontally arranged arm 56^b extends to the right as viewed in Fig. 5 and below the level of the hooked fingers a sufficient distance so as to supply the fleecing thread 9 immediately below the outer hooked fingers which have been thrust inwardly immediately over the outer portion of said horizontal arm 56^b at about the point 52 upon Fig. 2. Means are provided for holding this feed member 56 in proper position with the desired nicety of adjustment, said means consisting of an elongated slot 77 in the upper end of the vertical portion 56^a, into which slot fits with an upward and downward adjustment the outer end of a round bar 78, the inner end of which has a sliding adjustable fit in a hole in a block 80 secured to the upper surface of the inner cam holder 67. A set screw 81 through the block 80 holds the rod 78 in proper position after it has been adjusted longitudinally of itself and upon its axis affording the desired adjustment for the feed member. Near the upper end of the vertical portion 56^a of this feed member the thread coming from a suitable source (not shown) passes through a hook 82, then down through an eye 83 on the left-hand side of said vertical part 56^a toward its lower end and then said thread passes along the lower surface of the horizontal arm 56^b through a slot 84, from which it passes upward to the hooks through a hole 85 near the outer end of said arm. The construction and arrangement of the guide 76 for supplying outside the circle of needles the thread for the inner fleecing loops is shown in detail particularly in Figs. 7 and 8. This guide or feed member 76 is likewise supported from the inner cam holder 67^a by means of a similar block 80 receiving in its aperture a rod 78 adjustably held by a set screw 81, the outer end of which rod has an up and down adjustable fit into the slot 86 in the vertical portion 76^a of the guide or feed member 76. The upright portion 76^a is held upon said rod by a headed screw 87 having its head engaging said upright portion while the shank of said screw extends into the end of said rod 76. The upright portion 76^a of this feed member likewise passes down in front of the cam holder 67^a at a point where both the inside and outside hooked fingers will always be at inoperative position, but this upright portion 76^a is located outside of the circle of needles 27 so as not to interfere with the upraised needles. From the lower end of the upright portion 76^a there extends to the right as seen in Fig. 7 a horizontal arm 76^b extending immediately below the level of the inner hooked fingers to a point as 71 where the inner hooked fingers have been projected outward to engage the fleecing thread for the inside loops. The thread for this feed member 76 comes from a suitable source (not shown) through a hook 88 upon the upper end of the upright portion 76^a down through an opening 89 near the left end of the horizontal arm 76^b, from which hole the thread passes along the bottom of said arm 76^b in a downwardly opening slot 90 and thence upward through an opening 91 into the hooks of the inner hooked fingers.

What we claim as new and desire to secure by Letters Patent is:

1. In a circular independent-needle knitting-machine, the combination of a needle-cylinder, needles carried thereby, two feeds therefor, means for raising and lowering said needles to knit at each feed, a dial arranged within the circle of needles, fingers mounted thereon with hooks at their outer ends and adapted to be projected through said circle of needles, means at one feed for projecting said fingers out between the raised needles and drawing them back whereby loops of fleecing thread are formed extending inward from said raised needles and are left on the back of the fabric, an annular dial arranged outside the circle of needles, fingers mounted thereon with hooks at their inner ends and adapted to be projected through said circle of needles and means at the other feed for projecting said outer fingers in between the raised needles and drawing said fingers back whereby loops of another fleecing thread are formed extending outward from said raised needles and are left on the front of the fabric.
2. In a circular independent-needle knitting-machine, the combination of a needle-cylinder, knitting needles carried thereby, a plurality of feeds therefor, means for raising and lowering said needles to knit at each feed, a dial arranged within the circle of needles, fingers mounted thereon with hooks at their outer ends and adapted to be projected through said circle of needles, means at certain feeds for projecting said fingers out between the raised needles and drawing them back whereby loops of fleecing threads are formed extending inward from said raised needles and are left on the back of the fabric, an annular dial arranged outside the circle of needles, fingers mounted thereon with hooks at their inner ends and

adapted to be projected through said circle of needles and means at other feeds for projecting said fingers in between the raised needles and drawing said fingers back whereby loops of other fleecing threads are formed extending outward from said raised needles and are left on the front of the fabric.

3. In a circular independent-needle knitting-machine, the combination of a needle-cylinder, knitting needles carried thereby, a plurality of feeds therefor, means for raising and lowering said needles to knit at each feed, a dial arranged within the circle of needles, fingers mounted thereon with hooks at their outer ends and adapted to be projected through said circle of needles, means at alternate feeds for projecting said fingers out between the raised needles and drawing them back whereby loops of fleecing threads are formed extending inward from said raised needles and are left on the back of the fabric, an annular dial arranged outside the circle of needles, fingers mounted thereon with hooks at their inner ends and adapted to be projected through said circle of needles and means at the other feeds for projecting said fingers in between the raised needles and drawing said fingers back whereby loops of other fleecing threads are formed extending outward from said raised needles and are left on the front of the fabric.

4. In a circular independent-needle knitting-machine, the combination of a needle-cylinder, knitting needles carried thereby, a plurality of feeds therefor, means for raising and lowering said needles to knit at each feed whereby a plain basic web is formed having its wales on the front side and its connecting threads on the back side of said web, a dial arranged within the circle of needles, fingers mounted thereon with hooks at their outer ends and adapted to be projected through said circle of needles, means at certain feeds for projecting said fingers out between the raised needles and drawing said fingers back whereby loops of other fleecing threads are formed extending outward from said raised needles and are left on the front of the fabric with the needle ends of said loops back of the wales of the fabric.

of fleecing thread are formed extending inward from said raised needles and are held back of the fabric and means for casting the needle-ends of said fleecing thread loops off over the tops of the needles whereby the needle ends of said loops are held back of the wales and in front of the connecting threads of the fabric.

5. In a circular independent-needle knitting-machine, the combination of a needle-cylinder, knitting needles carried thereby, a plurality of feeds therefor, means for raising and lowering said needles to knit at each feed whereby a plain basic web is formed having its wales on the front side and its connecting threads on the back side of said web, a dial arranged within the circle of needles, fingers mounted thereon with hooks at their outer ends and adapted to be projected through said circle of needles, means at certain feeds for projecting said fingers out between the raised needles and drawing said fingers back whereby loops of fleecing thread are formed extending inward from said raised needles and are held back of the fabric, means for casting the needle-ends of said fleecing thread loops off over the tops of the needles whereby the needle ends of said loops are held back of the wales and in front of the connecting threads of the fabric, an annular dial arranged outside the circle of needles, fingers mounted thereon with hooks at their inner ends and adapted to be projected through said circle of needles and means at other feeds for projecting said fingers in between the raised needles and drawing said fingers back whereby loops of other fleecing threads are formed extending outward from said raised needles and are left on the front of the fabric with the needle ends of said loops back of the wales of the fabric.

In witness whereof we have affixed our signatures, this 29th day of February 1916. 90

WALTER STAFFORD.
ROBERT C. HOLT.
